PREPAYMENT ELECTRICITY METER

Arthur Zenkner, Zug, Switzerland, assignor to
Landis & Gyr, A-G., a body corporate of Switzerland

Application December 22, 1936, Serial No. 117,130
In Switzerland December 26, 1935

3 Claims. (Cl. 194—3)

The present invention relates to a novel and improved coin controlled or prepayment electricity meter and more particularly to such a meter which is adapted to make a basic or initial charge as a part of the rate schedule for electric power.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrate one embodiment of the invention, and together with the description, serve to explain the principles of the invention.

Of the drawing:

Figure 1 is a diagrammatic view showing an illustrative and typical embodiment of the present invention;

Figures 2 and 3 are schematic, fragmentary views of modified embodiments of the invention.

Figure 4 is a detailed sectional view of the fixed charge setting mechanism.

The present invention, in certain of its aspects, is an improvement upon the prepayment meter disclosed in the patent to Onesime Borel, No. 1,962,923, granted June 12, 1934, but in other respects is of more general application. It has for its object the provision of a prepayment meter in which a portion of the deposited coin is appropriated to pay a predetermined and fixed initial charge, which charge is accumulated as a function of time. A further object is the provision of a prepayment meter in which a predetermined portion of the deposited coins is appropriated to pay a basic rate as the coins are deposited until the full basic rate is satisfied and are then further appropriated in accordance with time as other coins are deposited.

In accordance with the present embodiments of the invention, a main current controlling switch is closed by the deposit of a coin and is opened by consumption of power or by time. As the coins are deposited, they permit operation of the switch controlling and closing devices, and defer the opening of the switch in accordance with the number or value of the deposited coins. As the coins are deposited and tend to close the switch, a fixed and predetermined portion of their value

is appropriated to pay for a basic or initial time charge and this is deducted from their effect on the switch controlling mechanism, while at the same time, the power consumed by the customer also serves to tend to open the switch.

5

More specifically, assuming that the customer is to be charged for power at the rate of 5 cents per k. w. h., in addition to basic charges of 50 cents at the beginning of each month and 1 cent a day: Upon the customer depositing 25 cents 10 in the meter, 20 cents of this coin is credited to the basic charge and the customer may use 1 k. w. h. When the customer inserts the next coin, 80% of it may be credited to the basic charge, and with the third coin, only 10 cents 15 would be credited to the basic rate, leaving the customer a total of 25 cents credit for power. Thus, the customer could use 5 k. w. h. The insertion of a fourth coin would entitle the customer to a full 5 k. w. h. of power. Of course, 20 other values, rates and proportions may be provided for by different gearing.

Referring now in detail to the illustrative embodiment of the invention as shown in Figure 1, the construction in many parts may be identical 25 with that shown and described in the patent to Borel and as there shown, the metering means for measuring the consumption of electrical energy in an induction watt-hour meter of conventional construction which comprises the usual 30 meter disc 1 and driving magnets 2 to drive the disc proportionately to energy consumption.

The meter disc 1 drives a cut-out switch operator 3 of conventional construction through a differential 4, 5, and 6. Gear 4 is journaled on 35 shaft 8, which shaft fixedly carries the support for planet gear 5, whereby movement of gear 5 produces rotation in shaft 8. Gear 6 is fixed to shaft 7 and is in mesh with planet gear 5. Shaft 7 is mounted independently of shaft 8 but in 40 alignment therewith so that it may rotate with respect to it. Cut-out switch operator 3 is directly formed on shaft 7. When the cut-out switch mechanism is returned to its original position by operation of the meter, the cut-out switch is 45 opened in the usual manner, interrupting the supply of current, until such time as it is closed by insertion of coins in the prepayment mechanism later to be described. The cut-out switch operator 3 has its shaft 7 rotatably connected to 50 the differential shaft 8, and is moved thereby to open or close the switch.

The prepayment device, into which the customer inserts one or more coins to close the switch and secure the delivery of an equivalent 55

amount of energy, comprises a pair of slotted discs 10, 11, mounted on shaft 12, disc 11 being fast to shaft 12, while the other disc 10 is loosely mounted on the shaft by means of a sleeve 13 to which is connected an actuating handle similar to handle 14 of the Borel patent, referred to hereinbefore. The customer inserts coins in the slots 15, linking the two discs together, and then turns an actuating handle, causing the upper disc 11 and shaft 12 to rotate exactly one-quarter revolution and releasing the coin at the end of the handle stroke in the usual manner.

At its upper end, shaft 12 carries a gear 16 fixed thereto and also a gear 17 rotatable relative to the shaft and gear 16 and spaced from gear 16 by means of a hub on gear 16. The gear 17 is also provided with a hub on the face of the gear which is adjacent the upper end of shaft 12. Surrounding the hub of gear 17 and positioned between the face of the gear and a supporting member on shaft 12 is a compression spring 18 which acts to force the underface of gear 17 into frictional engagement with the hub of gear 16.

The prepayment device is coupled to the cut-out switch by means of a differential gearing which transmits the actuation of the prepayment device to the cut-out switch at two predetermined and different ratios. As embodied, the gears 16 and 17 mesh with gears 19 and 20, respectively, gear 19 being fixed to shaft 21, while gear 20 is fixed to a sleeve 22 loose on said shaft. Sleeve 22 has fastened to its other end a differential gear 23, which meshes with a revoluble pinion 24 mounted on an arm fixed to shaft 21, and meshing with the other differential gear 25 fast to a sleeve 26. Sleeve 26 is loose on shaft 21 and at its upper end is connected by rods 26' to a bevel gear 27 which is pressed upwardly by means of the spring 27', which drives differential gear 6 through gears 28 and 29 spring 27' serving to hold the gears 27 and 28 lightly in mesh.

At the beginning of each monthly or other metering period, the actuation of handle 14 causes a quarter revolution of discs 10, 11, and gears 16, 17 for each coin deposited, and differential gear 23 and pinion 24 are moved thereby in unison to drive the differential gear 25, thereby accumulating on the cut-out switch mechanism 3 a reserve equivalent to one-half the value of the coin deposited. Due to the gear ratio employed, only one-half of the coin value is transferred so long as the gear 40 hereinafter referred to is free to move, but when the gear 40 is not free to move, the full value of the coin will be transferred to the cut-out switch operator 3 by suitably moving the gearing operating the same.

For increasing the ratio of the drive between the prepayment device and the cut-out switch, so that the customer will receive energy value for his money after the predetermined fixed charge has been paid, means are provided for holding one of the differential gears against rotation. Where the gears 16 and 17 are of the same size this doubles the rate of accumulation of surplus in the cut-out switch. As embodied, a pair of discs 30, 31 cooperate with a pivoted detent 33 loosely mounted on shaft 72, which prevents further rotation of the discs when they have been returned to zero. Shaft 32 carries a totalizing register, which is returned to zero when the fixed predetermined charge has been

fully paid, and comprises a pair of register wheels 34, 35 connected together by the usual transfer mechanism 36. The units wheel 35 and disc 30 are fixed to shaft 32, while the tens wheel 34 and disc 31 are fast to a sleeve 5 37 loosely mounted on the shaft.

This ratio changing mechanism is driven from sleeve 22, by means of gear 40 which drives sleeve 41 through gears 42, 43 and 44, and sleeve 41 is loosely journaled on a longitudinally slideable sleeve clutch 45, held against rotation on shaft 75', and pressed into clutching engagement with sleeve 41 by spring 46. At the end of sleeve 45 is a friction cup 47 which may be pressed inwardly to release the friction coupling between sleeves 41, 45, and permits the service man to set the fixed charge register 34, 35 at the beginning of each period. The resetting of the fixed charge mechanism is conveniently accomplished by the insertion of a 20 blunt pencil through a hole in the meter casing, pressing inwardly on the friction cup 47 and turning it until the register shows the proper predetermined fixed charge.

Other totalizing registers are provided for accumulating the totals of the energy metered, the coins deposited and appropriated in payment of the fixed charges, the coins appropriated in payment of energy, and the total of unappropriated coins.

The register for the total energy consumed comprises a totalizing register 50 of conventional construction which is driven directly from the meter through pinion 51.

The register for the total coins appropriated in payment of the fixed charges comprises the totalizing register 52 which is driven through a gear train comprising gears 53, 54, 55 from gear 44, and is actuated by any rotation of gear 17.

The register for the total coins appropriated by metered energy and accumulated against energy to be metered comprises the totalizing register 56 which is driven directly from gear 28, through pinion 57.

The register for the total unappropriated coins comprises a register 58 which is driven from the differential shaft 8 through gears 59, 60 in accordance with orbital movement of the differential pinion 5, and is driven forwardly as 50 coins are deposited, and reversely as they are appropriated by rotation of the meter disc.

As the differential pinion 5 is moved forwardly by the insertion of a coin, the switch is moved to closed position and its control mechanism is 55 then moved beyond open position, while as the meter disc rotates, the pinion 5 is reversely moved so as to appropriate the value of the coin and finally cause the switch to be opened.

By varying the ratio of gears 16, 17, 19 and 20, the percentage of the coins deposited which is appropriated for prepayment of the fixed charge may be varied as desired and by choosing a suitable ratio prepayment of the fixed charge in full may be required before any current is supplied through the meter. With the gear ratio as shown, one-half the value of the deposited coins is appropriated until the fixed charge has been paid; but if a higher gear ratio is chosen for the gears 17, 20, so that gears 20 and 40 70 are driven faster than gear 19 and planet 24, then a smaller percentage of the coin value will be used to pay the fixed charge as gears 40 and 42 and the mechanism driven thereby will be driven to its fully paid position sooner.

Means are provided in accordance with the present invention for accumulating a time charge which is subsequently paid for by a fixed proportion of the deposited coins. As embodied, 5 there is provided a timing device, such as the rotor 70 of a synchronous clock, which drives the gear 71 through shaft 72, this gear meshing with sun gear 73 of the differential 74, while the sun gear 75 is relatively non-rotatable with 10 reference to the face of clutch 45. Sun gear 75 is mounted on a shaft 75' slidably but non-rotatably mounted within the sleeve 45 to which the friction cup 47 is attached at the opposite end. Rotation of the cup 47 will thus be transmitted to the sun gear 75. Planetary gear 76 15 of the differential 74 is fast to the shaft 32 to which are secured the drum 35 and the cam disc 30, as well as the units drum of the totalizing register 52. Rotor 70 turns slowly and advances the cam discs 30 and 31 slowly at a predetermined rate, thereby accumulating a time charge which must be paid for by deposited coins. Planet gear 76 is thus advanced by a time factor and is returned to a position where 20 the spring urged pawl 33 engages in the notches of both cam discs 30 and 31 by the insertion and partial appropriation of deposited coins.

In the operation of the described embodiment, the insertion of a coin into the slots 15 permits the disc 11 to be rotated by rotation of the disc 10, and this causes rotation of the gears 16 and 17 and thereby rotation of the gears 19 and 20. Gear 20 rotates gears 40, 42, 43, 44 and 75, causing a reverse rotation of sun 25 gear 73 tending to return the drums 34 and 35 to zero. When a sufficient number of coins has been deposited, the pawl 33 locks the discs 30 and 31 against further backward rotation and thereby holds the gears 73, 75 and 76 against 30 movement, so that any further value of the coins is credited entirely to the current controlling switch. Rotation of gear 40 rotates sun gear 23 and planet gear 24 is simultaneously rotated by gear 19 through shaft 21 and the 35 movement of sun gear 23 and planet gear 24 rotates sun gear 25. Gear 25 is fast to gear 21 to drive the sun gear 6 of the switch controlling mechanism through gears 28 and 29.

Thus the switch controlling mechanism, of 40 known construction, is set to close the switch and then advance it so that a corresponding amount of power may be delivered to the customer.

As the power is measured by the meter 1, sun 45 gear 4 is rotated to reversely move the switch controlling mechanism and tend to open the switch which is directly actuated by the planet gear 5.

The time charge is subtracted from the value 50 of the deposited coins by means of the differential 74 which has its sun gear 73 moved to advance the drums 34 and 35, as well as discs 30 and 31, by the rotor 70, and this advance sets the mechanism so that it will later appropriate a portion of the deposited coins to pay for the time charge, at the same time crediting the remainder of the deposited coin value to the current controlling switch. When all 55 of the fixed charges have been paid, the differential sun gear 23 is locked against rotation and the full value of the deposited coins is credited to the switch controlling mechanism.

Figure 3 illustrates a modified embodiment of the invention in which the meter drives a gear 75 fixed to sun wheel 81 of the differential 82,

the rotor 70 drives gear 83, which is freely mounted to rotate on its supporting shaft 84'. Gear 84 is fixed to said supporting shaft, as is also a collar 83'. Spring 86' surrounds said shaft and is compressed between gears 83 and 84, forcing gear 83 against collar 83', thus frictionally connecting gear 83 through the supporting shaft 84' to gear 84 and cause the gears to rotate together while the deposited coins serve to rotate a gear 85. Fixed to gear 84 is a stop pin 86 which may be set either by the fixed charge knob 47 or by the timing rotor 70, and this stop pin is adapted to limit the movement of the arm 87 fixed to the shaft 88. Shaft 88 carries gear 89 which meshes with gear 90 fastened to the sun gear 91, while gear 90 also meshes with gear 92 which is frictionally coupled to the coin controlled gear 85 by the same type of clutch as connects gears 83 and 84. Gear 85 meshes with the gear 93 fixed to the shaft 94 supporting the planet gear 96 travelling between sun gears 91 and 97 and sun gear 97 is fast to gear 98 meshing with the gear 99 which is fast to sun gear 100 of the differential 82. Planet gear 101 meshes with the sun gears 81 and 100, and is mounted on the switch controlling shaft 103.

In the operation of this embodiment, the switch controlling shaft 103 is moved in one direction by the meter driven gear 81 so as to open the switch, while it is moved in the other direction by gear 100, and gear 100 may be advanced by the coin controlled gear 90 or 93. As the first coins are deposited, gears 90 and 93 are both rotated until stop arm 87 contacts 30 with the stop pin 86, after which pinion 96 is revolved with gear 90 held stationary so as to rotate gear 100 and revolve planetary gear 101. With the passage of time, stop pin 86 is further advanced by time, so that the next coin 35 will be partially appropriated as it is deposited to pay for the time charge, the remainder of the coin being credited to the switch mechanism.

In Figure 2 there is shown a further modified embodiment of the invention in which the switch controlling shaft 103 is directly operated by planetary gear 101 meshing with the meter driven sun gear 81 and the time and coin controlled sun gear 100. The timing rotor 70 drives sun gear 73 in the direction shown by the solid arrow, causing planetary gear 76 to move at half speed in the same direction so as to move the stop arm 87 in the same direction, while sun gear 75 is reversely moved by the coin controlled handle 14 through gears 110, 111. Handle 14 also moves gears 112, 113 to turn sun gears 114 and 115 in opposite directions until arm 116 engages stop arm 87, after which planetary gear 117 revolves to rotate gear 100, thereby revolving gear 101. Thus the deposited coin is first simultaneously credited to the fixed charge device and the switch controlling means, until arms 116 and 87 are in engagement, indicating 40 full payment of the fixed charge, and thereafter the full value of the coin is credited to the switch controlling means until a further time charge has been accumulated, after which this charge is again paid by the deposit of another coin.

The invention in its broader aspects is not limited to the specific mechanisms shown and described but departures may be made therefrom within the scope of the accompanying claims without departing from the principles of 45

the invention and without sacrificing its chief advantages.

What I claim is:

- 5 1. In a prepayment device, the combination of a power meter, a timing device, a coin controlled device, a switch controlling device to limit the supply of power, mechanism including a differential gear train connecting said power meter to said switch controlling device, a second differential operated by said coin controlled device, a third differential operated by said timing device, means connecting said third differential to said second differential whereby operation of the latter affects the drive of said third differential, 10 means interconnecting said second differential with said first differential whereby operation of said first differential by said meter is affected by said second differential, and a stop limiting the movement of the time controlled device by 15 the coin controlled device.
- 20 2. In a prepayment device, the combination of a power meter, a timing device, a coin controlled device, a switch controlling device to limit the supply of power and adapted to be moved in opposite directions, means connecting the power meter to the switch controlling device for moving the latter in one direction to limit the supply

of power, means connecting the timing device to said switch controlling device for also moving the latter in said same direction and means connecting the coin controlled device to said switch controlling device for moving the latter in another direction to obtain a supply of power, a stop positioned by the timing means, a member connected with the meter and said coin control device and movable against said stop thereby and serving to reduce the movement of the switch controlling device.

25 3. In a prepayment device, the combination of a power meter, a timing device, adjustable stop means including a variable element, a coin controlled device, a switch controlling device to limit the supply of power, a differential connected with said meter and said switch controlling device, a second differential connected to said first differential and said coin controlled device, one of the gears in the second differential being controlled in its movement by said adjacent stop, a third differential connected to said timing device and said coin control device, and means connecting said third differential with said variable element of said stop.

25 ARTHUR ZENKNER.
